(57) **CLAIM**

The ornamental design for a shower chair, as shown and described.

DESCRIPTION

FIG. 1 is a front, perspective view of a shower chair in accordance with the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, perspective view of the shower chair of FIGS. 1-7 in an alternative configuration with a center cover plate of the seat removed.

The broken lines shown in the drawings illustrate portions of the shower chair that form no part of the claimed design.

1 Claim, 7 Drawing Sheets
